UNITED STATES PATENT OFFICE.

ALBERT BORDEN, OF ST. LOUIS, MISSOURI.

VALVE-OPERATING DEVICE AND ALARM.

SPECIFICATION forming part of Letters Patent No. 634,744, dated October 10, 1899.

Application filed February 9, 1899. Serial No. 705,137. (No model.)

To all whom it may concern:

Be it known that I, ALBERT BORDEN, of the city of St. Louis, State of Missouri, have invented certain new and useful Improvements 5 in Valve-Operating Devices and Alarms, of which the following is a full, clear, and exact description, reference being had to the accompanying drawings, forming a part hereof.

My invention relates to valve-operating devices and alarms; and it consists of the novel construction, combination, and arrangement of parts hereinafter shown, described, and claimed.

Figure 1 is a front elevation of my improved 15 device, parts thereof being in section to more clearly illustrate the same. Fig. 2 is a side elevation of the device. Fig. 3 is a plan view thereof. Fig. 4 is an enlarged cross-sectional view taken approximately on the line 20 4 4 of Fig. 3. Fig. 5 is a horizontal sectional view taken approximately on the line 5 5 of Fig. 2.

Referring by numerals to the accompanying drawings, 1 indicates a suitable base, to 25 the lower front face of which is secured in any suitable manner the base 2 of a specially-formed casting, and from one side of this base 2 projects forwardly an arm 3, with the outer end of which is formed integral a valve-casing 30 4, in which valve-casing is formed four horizontally-arranged partitions 5, thereby dividing the valve-casing into five compartments. Formed through the centers of the partitions 5 are vertically-alined apertures or valve- 35 openings 6, and operating through these valve-openings is a valve comprising two end disks 7, intermediate of which is the central disk 8, said disks being connected by the webs 9. Discharging into the central one of the compartments within the valve-casing is a suitable 40 connection 10, through which fluid under pressure is discharged into said central chamber, and leading from the chambers immediately above and below said central chamber are suitable tubular connections 11, the same leading to the valve or other mechanism that is operated by my improved device.

Leading from the top and bottom chambers within the valve-casing are suitable tubular 45 connections 12, that combine with or are connected to a waste or discharge pipe 13. Formed integral with the left-hand side of the

valve-casing 4 is a laterally-projecting arm 14, through which is formed a screw-threaded aperture, in which operates the exteriorly-screw-threaded lower end of a vertical post 15, the same being provided with an integral disk 16 adjacent its upper end. Seated in the upper end of this post is a pin 17, that forms a fulcrum for a horizontally-arranged arm 18, one end of which projects to a point directly over the center of the valve-casing 4, and a suitable connection 19 is made from said end of the arm 18 to the upper end of the valve that operates within said valve-casing. 65 A stuffing-box 20 is located in the top of said valve-casing around this connection 19. Upon the opposite end of this arm 18 is adjustably located a weight 21, which counterbalances the weight of the valve within the valve-casing 4, and passing through said arm at equal distances on each side from the fulcrum thereof are screw-threaded pins 22, with the lower ends of which are formed integral the heads 23, into which screw the contact-points 70 24, that lie immediately over the face of the disk 16. A pair of ears 25 are formed integral with the top of the arm 18 immediately above the fulcrum thereof, and between said ears is fulcrumed a horizontally-arranged 75 tube 26, the ends thereof being closed by the caps 27 and 28 and there being a ball 29 located within said tube. Formed integral with the cap 28 is a ring 30, through which passes a vertically-moving rod 31, the lower 80 end of which is screw-threaded, and adjusting-nuts 32 are located upon said screw-threaded lower end, one above and one below said ring 30.

A horizontally-arranged arm 33, provided 90 at one end with a weight 34 and at its opposite end with a ring 35, is pivoted to the outer end of the bracket 36, that is carried by the base 1, and on top of each end of said arm 33 is formed a contact-point 37. Pivoted and adjustably held upon the bracket 36 immediately above the arm 33 is a short arm 38, the outer end of which carries a contact-point 39, that is positioned immediately above the right-hand one of the contact-points 37, and 95 adjustably held immediately above the left-hand one of the contact-points 37 is a contact-point 40. An electrical conductor 41 leads from the arm 38 to one pole of a suitably-located

cated battery 42 and from thence to one of the binding-posts of an alarm-bell 43, and another conductor 44 leads from the opposite binding-post on said bell to the end of the arm 33. Leading from the contact-point 40 to the conductor 41 is a short conductor 45. Passing through the ring 35 on the end of the arm 33 is the screw-threaded lower end of a vertically-moving rod 46, the same being provided with adjusting-nuts 47, one above and one below said ring 35.

Assuming that the parts are balanced or are in the positions shown in Fig. 1 and that the rod 31 is moved upwardly when the lower nut 32 upon said rod strikes the ring 30, carried by the cap 28, said ring and cap, together with the end of the tube 26, on which said cap is located, will be elevated and the ball 29 will roll to the opposite end of said tube. When this movement takes place, the side of the tube into which the ball has rolled will engage against the upper end of the left-hand one of the adjusting-screws 22 and will depress the same, which will lock the bar 18 upon the pivot-pin 17, throwing the weighted end downwardly until the left-hand one of the contact-points 24 strikes against the disk 16, and this movement necessarily raises the opposite end of said bar 18 and elevates the valve within the valve-casing. As said valve is drawn upwardly in said valve-casing communication will be established between the chambers into which the inlet-pipe 10 leads and the chamber immediately below said first-mentioned chamber and at the same time communication will be established between the chamber immediately above the chamber in which the inlet-pipe 10 leads and the top chamber or the one from which the discharge-pipe 12 leads. Consequently if compressed air is passing through the valve said compressed air will enter the pipe 10, to be discharged therefrom into the central one of the chambers between the partitions 5, and pass from thence downwardly into the next adjacent chamber, from thence through the top one of the tubular connections 11 and be delivered to a point where it is desired to utilize said compressed air, and simultaneous with this action the opposite pipe 11 becomes an exhaust-pipe and the back pressure through said pipe discharges into the chamber above the central chamber, in which the pipe 10 discharges, and from thence the compressed air discharges into the top chamber and through the discharge or exhaust pipe 12. When the rod 31 moves downwardly, the nut 32 thereon will strike against the upper side of the ring 30 and a reverse movement of the parts just described will take place and the valve will be lowered, so that the top disk 7 closes the opening through the top partition 5, the central disk 8 closes the opening in the partition immediately below the central chamber, into which the inlet-pipe 10 leads, and communication will be established between the two lowermost chambers and be-

tween the central chamber and the one immediately above it. The distance that the rod 31 has to move before the tube 26 is actuated is regulated by the adjusting-nuts 32 upon the screw-threaded portion of said rod. It is essential that the movement of the rod 46 be simultaneous with that of the rod 31. The adjusting-nuts 47, located upon the rod 46, are normally farther apart than are the adjusting-nuts 32 upon the rod 31, said nuts being so located as that they will not engage the ring 35 on the end of the fulcrumed arm 33 to sound the alarm until after the valve-operating mechanism has actuated. Thus the alarm is sounded only at a time after the valve has been actuated, and the rod 31 continues to move upwardly or downwardly, as the case may be, thereby endangering breakage of the various parts of the valve-actuating mechanism. When the rod 46 continues in its upward movement, the lower one of the nuts 47 thereon will strike against the under side of the ring 35, thus raising said ring and the end of the arm 33 upon which said ring is located, and as said end of the arm moves upwardly the right-hand one of the contact-points 37 will engage against the contact-point 39, thereby closing the circuit through said arm 33, bar 38, conductor 41, battery 42, bell 43, and conductor 44. When the rod 46 descends past its normal lowered position, the upper one of the nuts 47 will engage upon the top of the ring 35 and a contact will be made between the left-hand one of the contact-points 37 and the contact-point 40, thereby closing the circuit and sounding the bell 43. The operator or attendant will immediately know that the rod 31 is not operating properly when the bell sounds.

A device of my improved construction is especially applicable for use in connection with thermostats, which thermostats are used to elevate the rods 31 and 46, and the compressed fluid that passes through the valve may be led to and through the valve that is located in the pipe that supplies the hot air, water, or steam to the heating system in the building in which the valve-operating device and alarm are located.

I claim—

1. In a device of the class described, a vertically-arranged valve-casing, a valve operating therein, a fulcrumed arm connected at one end to said valve, a weight arranged on the opposite end of said arm for counterbalancing the weight of the valve, means whereby the movement of the arm is limited, ears projecting upwardly from the center of said arm, a tube fulcrumed between said ears, which tube is provided with closed ends, a ball located within said tube, and means whereby one end of the tube is elevated or lowered, substantially as specified.

2. In a device of the class described, a vertically-arranged valve-casing, a valve operating therein, a fulcrumed arm connected at one end to said valve, a weight arranged on

- the opposite end of said arm for counterbalancing the weight of the valve, means whereby the movement of the arm is limited, ears projecting upwardly from the center of said arm, a tube fulcrumed between said ears, which tube is provided with closed ends, a ball located within said tube, means whereby one end of the tube is elevated or lowered, a fulcrumed arm 33, contact-points carried by each end of said arm, contact-points located above said first-mentioned contact-points, a suitably-located bell, connections from the last-mentioned contact-points and from the arm 33 to said bell, and means whereby one end of the arm 33 is elevated or lowered simultaneously with the elevating or lowering of the tube, substantially as specified. 3. In a device of the class described, a vertically-arranged valve-casing containing a plurality of compartments, tubular connections to said compartments, a valve operating vertically through said casing to open and close communication between said compartments, a bracket integral with the valve-casing, a screw-threaded post operating in said bracket, a disk formed integral with said post, a pin seated in the top of said post, an arm fulcrumed upon said pin, one end of which arm is connected to the valve, the opposite end being provided with a weight which counterbalances the weight of said valve, screw-threaded pins passing through said arm at equal distances from the center thereof, contact-points adjustably carried by the lower ends of said pins, ears formed integral with and extending upwardly from the center of said arm, a tube having closed ends fulcrumed between said ears, a ball located in said tube, and means whereby one end of said tube is elevated or lowered, substantially as specified.

In testimony whereof I affix my signature in presence of two witnesses.

ALBERT BORDEN.
